UNITED STATES PATENT OFFICE.

WILLIAM H. MUZZY, OF DAYTON, OHIO, ASSIGNOR TO THE NATIONAL CASH REGISTER COMPANY, OF DAYTON, OHIO, A CORPORATION OF OHIO, (INCORPORATED IN 1906.)

COMBINATION TYPE-WRITING AND ADDING MACHINE.

1,013,211.

Specification of Letters Patent.

Patented Jan. 2, 1912.

Application filed March 19, 1908. Serial No. 422,081.

To all whom it may concern:

Be it known that I, WILLIAM H. MUZZY, a citizen of the United States, residing at Dayton, in the county of Montgomery and 5 State of Ohio, have invented certain new and useful Improvements in Combination Type-Writing and Adding Machines, of which I declare the following to be a full, clear, and exact description.

10 This invention relates to improvements in combined typewriting and adding machines.

The principal object of the invention is to provide typewriting and adding mechanisms, so connected that the proper additions 15 are enforced according to amounts printed by the typewriter.

With this and incidental objects in view, the invention consists in certain novel features of construction and combination of 20 parts, the essential elements of which are set forth in appended claims and a preferred form of embodiment of which is hereinafter specifically described with reference to the drawings which accompany, 25 and form part of this specification.

Of said drawings: Figure 1 represents a front elevation of the typewriting and adding machines, with the platform upon which the machines are mounted in section, and 30 showing the connections embodying the present invention. Fig. 2 represents a transverse section taken on the line 2—2 of Fig. 1, showing the auxiliary key board in section. Fig. 3 represents a transverse section through the typewriter on line 3—3 of Fig. 1. Fig. 4 represents a detail section of 35 the key locking frame of the typewriter and its coöperating parts, in a partially operated position, also showing in dotted lines 40 the parts in a completely operated position. Fig. 5 represents a detail perspective of the typewriter space bar and connection. Fig. 6 represents a horizontal section through the latch controlling mechanism; and Fig. 45 7 represents a horizontal section through a row of the auxiliary keys of the adding machine.

There has been shown in the drawings, as 50 one illustration of the invention, a standard make of a Remington typewriter and a Burroughs adding machine with connections, such that the keys of the adding machine, which are normally locked, will become unlocked by the operation of the digit 55 keys of the typewriter, and the latter keys

will then become locked and will only be released when corresponding keys and the operating handle of the adding machine have been operated. An auxiliary key board is pivotally mounted upon the adding 60 machine and is so arranged that, when in place, the keys thereof will register with the corresponding keys of the permanent key board of the adding machine, so that a manipulation of the former keys will 65 actuate the latter. The connections and additions to the several machines may be disconnected and readily removed, so that each machine may be used independently of the other. 70

Typewriter.—As previously described, the style of machine shown in the drawings is that of the Remington type, but it is to be distinctly understood that this invention is not to be limited to this style of machine, 75 as any other well known type may be employed with equal facility.

The key board comprises four rows of keys 1 and a space bar 2, all of which are pivotally mounted at their rear ends upon a transverse rod 3, and held in their normal elevated position by leaf springs 4 secured to a bar 5, the rod 3 and bar 5 being suitably supported by the side frames 6 of the machine. The key levers 1 are connected to 80 their respective type bars 7 by links 8, 9 and 10, the said type bars being pivotally mounted upon short stub shafts 11 and arranged to be swung into contact with a platen 12 upon the operation of key levers 85 1, as is well understood in the art. The upper row of key levers 1 is composed of the ten digit keys, of which nine (from 1 to 9) are connected to levers 13 by links 14, the 90 said levers being pivotally mounted at their rear ends upon a transverse rod 15, which is suitably secured within a base 16, upon 95 which the typewriting and adding machines are mounted. Each of the levers 13 is provided at its forward end with a link 17, the lower end of which is connected to a lever 18 mounted on a transverse shaft 19. The forward end of each lever 18 is provided with a spring pressed pawl 20, which is limited in its movements by stop pin 21, and is 100 arranged, when operated, to engage a gear wheel 21* and turn said wheel forward one tooth. This wheel 21* is fast to a disk 23, which is journaled upon a transverse shaft 24, and is formed with a notch 25 in its 110

periphery. It is to be understood that there is a disk 23 for each lever 13. A transverse rod 26 provided with an anti-friction sleeve 26^a projects in the notches 25 of the disks 23, 5 and is supported by the lower ends of links 28. These links 28 are pendent from the forward ends of levers 29, which are journaled upon the forward one of a series of transverse shafts 22 and are normally held 10 up at their forward ends by coil springs 30, which connect them to the frame of the machine.

It will be seen from the above that when one of the disks 23 is rotated by its pawl 20, 15 the rod 26 is forced out of the notch 25 and the links 28 thus drawn down. This action of the links also draws down the forward ends of the levers 29, so that locking lugs 38 projecting upward therefrom are moved 20 from behind a cross bar 39 of the locking frame 31, and thus permits the frame 31 to be drawn rearward by its spring 36 into the position shown in Fig. 4 in which its lugs 35 will contact with the hook ends of 25 the latches 34. The levers 29 are also provided with lugs 40, each normally supporting a pivoted latch 41. When the levers 29 are depressed, as above described, the lugs 40 permit the latches 41 to descend and rest 30 on the cross bar 39 of the frame 31, so that when this frame is subsequently released from the latches 34 by the operation of the space bar above described, the frame will spring rearward under the levers 13, and 35 the latches 41 will descend in front of the bar 39 and thus lock the frame 31 in position to intercept any movement on the part of levers 13. The result of this operation is to lock all the digit keys of the typewriter. 40 Should any particular key of the typewriter be operated a plurality of times in printing a certain numeral, its proper lever 18 will be operated correspondingly and its proper disk 23 fed forward a corresponding 45 number of teeth. It will be understood that as long as any one of the disks 23 is displaced from its normal position, as shown in Fig. 4, the links 28 will be held down and the levers 29 held in their depressed position 50 with the latches 41 in front of the bar 39, which will prevent the frame 31 being operated. It thus becomes necessary to return any of the displaced disks 23 to their normal positions in order to unlock the digit keys 55 of the typewriter. This backward movement of the disks is effected by connections with the adding machine as follows: Each of the transverse shafts 22, which is suitably supported in the base of the machine, is 60 provided with a pendent arm 42, provided at its lower end with a pin 43. Each of these pins projects into an incline slot 44 formed in the rear end of a lever 45, said levers being all fulcrumed on the shaft 19 5 and each of the same provided at its forward

end with a spring pressed pawl 46, which is limited in its movement by a pin 47. The pawls 46 are arranged to engage with gear wheels 46^a, secured to the opposite side of disks 23 from gear wheels 21^a, and turn 70 said disks in a reverse direction from that in which they are turned by pawls 20. The pawls 20 and 46 are substantially identical and each of the same normally occupies a position out of the path of the teeth of its 75 respective gear wheel. Each disk 23 is also provided with a stop lug 48 which contacts with a transverse shaft 49, upon which are mounted spring pressed restraining pawls 50 which engage the teeth of the gear wheels 80 to prevent overthrow of the same. After one of the disks 23 has been moved forward a certain number of teeth by the pawl 20, it is returned with a step by step movement by the pawl 46 which rotates it in the opposite 85 direction, this pawl acting to turn the wheel one tooth each time its corresponding shaft 22 is rocked.

Connected to the side arms 32 of the space bar 2 (Figs. 3 and 5), by slot and pin connections 32^a and 32^b respectively, are link bars 33, the lower ends of which are connected to locking pawls 34 pivoted at their rear ends upon stub shafts 27. The forward hook ends of these pawls engage downward 95 extensions 35 of the locking frame 31 and hold said frame in a retracted position. Upon depressing the space bar 2, the pins 32^b will contact with the lower ends of the slots 32^a and lower the links 33, which will 100 rock the pawls 34 out of engagement with the extensions 35, and allow springs 36 to draw the frame 31 under the levers 13 and thereby lock said levers and the digit keys 1 from operation. The frame 31 is limited 105 in its rearward movement by pins 37 projecting from the side walls of the platform 16.

It will be seen from the above description that the digit keys of the typewriter are 110 locked by the movement of the space bar.

Adding machine.—The Burroughs machine shown in the drawing is well known upon the market and needs no detail description, it being sufficient to state that it 115 comprises a plurality of keys 50^a, which determine the amounts that are to be registered and recorded upon the machine by the operation of the handle 51.

As previously mentioned, the adding machine is provided with an auxiliary key board 52 in which a plurality of banks of manipulative devices 53, in the shape of keys, are mounted corresponding to the keys 50 of the machine proper. This key board 120 52 is pivoted as at 54 to the casing 55 of the adding machine, and when said key board is in position, the keys 53 of the same are in vertical alignment with the corresponding keys 50. 125

A series of transverse rods 56, one for each horizontal row of keys 53, is loosely mounted in the side walls of the auxiliary key board 52 (Figs. 2 and 7), each rod being provided with rearwardly extending fingers 57, one for each key 53. Pins 58, extending laterally from the keys 53, contact with the upper sides of the fingers 57, and thereby rock the shafts 56 when said 10 keys are depressed. Upon the extreme left hand end of each rod 56 (Fig. 7), is a rearwardly extending finger 59, similar to the fingers 57, which plays in the upper forked end of a vertical rod 60, the latter being 15 suitably guided by a block 61 secured to the base of the machine. The lower end of each rod 60 is fastened to a rearwardly extending arm 62 secured to the right hand end of one of the transverse rods 22, which 20 extends through to the typewriter mechanism.

It will be seen from the above construction, that upon the operation of any manipulative device 53 in any row, its corresponding rod 22 will be rocked through means of the pin 58, fingers 57, 59 rod 60 and arm 62. The digit key of the typewriter, bearing the zero character, does not operate a lever 18, because the style of adding machine shown does not employ zero keys, it being understood that if the type of machine used in connection with the typewriter, employs a zero key or keys, the zero key of the typewriter would then actuate a 35 lever similarly to the remaining digit keys.

It will be seen from the above that, when any number of amount keys of the typewriter are operated, their disks 23 are correspondingly adjusted and the frame 31 released when the space bar is finally operated. As the keys of the adding machine are operated, the disks 23 are returned to their normal positions, which operation releases the levers 29, and the same passing 40 upward, raise the latches 41 from in front of the bar 39 and leave the frame 31 free to be forced forward again into its normal position, shown in Fig. 3. This operation of the frame is accomplished, through the medium of the shaft 19 upon which it is rigidly mounted, by means of an arm 65, which is rigidly connected to the opposite end of said shaft and is provided with a pin 66 with which the operating handle 51 of the 45 adding machine contacts just as the handle reaches the end of its forward movement. This operation rocks the shaft 19 sufficiently to move the frame 31 so far back that the lugs 38 again pass up to the rear of the bar 50 39 and lock the frame in position as shown in Fig. 3. It will be thus seen that, after the typewriter has been operated to print certain numerals and the space bar then actuated, the typewriter cannot be again operated for printing numerals until the add-

ing machine has been operated to add the numerals corresponding to those written on the typewriter. The operation of the adding machine must include, not only the pressing of the keys, but the operation of the handle before the mechanism under the typewriter is returned to a position in which the typewriter is again free for printing of numerals. When all the parts are in normal position with the lugs 48 of the disks 23 in contact with the transverse shaft 49, the manipulative devices of the adding machine will be locked from operation, because the disks 23 which are actuated by said manipulative devices have reached the limit of their 70 reverse movements.

As it is sometimes desirable to throw out the locking mechanism so that the typewriter may be employed for printing numerals, such as dates, which are not to be added, 75 on the adding machine, I provide means for accomplishing this result. This means comprises a shaft 71 suitably mounted in the casing and provided at its outer end with a thumb knob 72 by means of which it may 80 be adjusted and, having a lug 73, which, when the shaft is turned, contacts with one of the lugs 35 of the frame 31, and thus prevents the frame springing into locking position even when the amount keys and space 85 bar are operated. Shaft 71 is provided with arms 71^a arranged to contact with the tails of the pawls 20 and move the latter out of operative position when the shaft is rotated. It will, of course, be understood 90 that ordinarily the typewriter can be used with the lettered keys and space bar without any locking taking place, and that is only when the numeral keys are employed that the machine becomes locked until the corresponding amounts are entered on the adding 95 machine.

If the manipulative devices 53, of the rows, corresponding to the previously actuated digit keys of the typewriter are not 100 operated, it will be understood that the handle 51 cannot be completely operated, because the frame 31 is locked against return by the pawls 41. The handle can be released from this position by tilting the 105 platform 16 manually or in any desired manner and tripping the pawls 41, so that the handle can complete its stroke. It is, of course, to be understood that upon the operation of the manipulative devices 53, 110 the keys 50 of the adding machine proper are set so as to determine the amount that is to be registered and recorded upon the 115 operation of the handle 51.

In the use of combined typewriting and 120 adding machines in which statements are made out upon the typewriter and the items registered upon the adding machine, mistakes are frequently made by the operator 125 striking the wrong keys of the adding ma- 130

chine, with the result that in writing out the total upon the typewriter as shown by the registering wheels, an erroneous statement will be rendered. With the above described 5 interlocking mechanism, the chances of such mistakes are reduced to a minimum, for while the operator is not compelled to depress the proper keys to enable the complete 10 operation of the machine, he is compelled to operate keys of the rows in which the proper keys are located, and knowing that he has to operate keys of certain rows, the danger of mistake is greatly minimized, if not entirely eliminated.

15 While the form of device here shown and described is admirably adapted to fulfil the objects primarily stated, it is to be understood that it is not desired to confine the invention to one form of embodiment here 20 disclosed, for it is susceptible of embodiment in various forms, all coming within the scope of the claims which follow.

What is claimed is:

1. In a machine of the class described, the 25 combination with a typewriting mechanism including numeral keys, of an adding mechanism including numeral keys manually operable independently of the numeral keys of the typewriting mechanism, and means for 30 compelling corresponding manual operations of the keys of the two mechanisms.

2. In a machine of the class described, the combination with a typewriter mechanism including numeral keys, of an independently 35 operated adding mechanism, a lock for the numeral keys of the typewriter, and means for operating the lock by an element of the adding mechanism.

3. In a machine of the class described, the 40 combination with a typewriter having operating keys, of an adding mechanism having keys operable manually independently of the keys of the typewriter, and connecting devices compelling the manual operation of 45 corresponding keys of the typewriter and the adding mechanism.

4. In a combined typewriting and adding machine, the combination with the digit 50 keys of the typewriter, of a lock for said keys, an adding mechanism, connecting means compelling an operation of the adding mechanism for unlocking said keys, and devices for disabling said connecting means.

5. In a combined typewriting and adding 55 machine, the combination with the digit keys of the typewriter, of a space bar, a lock for said keys controlled by the space bar, an adding mechanism, and means requiring an operation of the adding mechanism for unlocking said keys.

6. In a combined typewriting and adding machine, the combination with the digit 60 keys of the typewriter, of a space bar, a lock for said keys controlled by the space bar and keys, and manipulative devices for

an adding machine corresponding to the digit keys for controlling the unlocking of said keys.

7. In a combined typewriting and adding machine, the combination with the digit 70 keys of the typewriter, of a space bar, a movable frame for locking said keys controlled by the space bar and keys, and manipulative devices for an adding machine for controlling the unlocking of the keys. 75

8. In a combined typewriting and adding machine, the combination with the digit 80 keys of the typewriter, of a space bar, a lock for said keys controlled by the space bar, manipulative devices for an adding machine for controlling the lock, and an operating handle for an adding machine also controlling the lock.

9. In a machine of the class described, the combination with a typewriting mechanism, 85 of an independently operated adding mechanism, including keys and an operating handle, a lock for the typewriter mechanism, and devices for controlling the lock from both the keys and handle of the adding 90 mechanism.

10. In a machine of the class described, the combination with a typewriting mechanism, including keys, of an adding mechanism, devices set differentially for locking 95 the typewriter keys by the operations of said keys, and means controlled by the adding mechanism for returning the locking devices to their normal positions to unlock the keys. 100

11. In a combined typewriting and adding machine, the combination with the digit 105 keys of a typewriter, of a space bar, a movable frame for locking the keys controlled by the space bar, manipulative devices of an adding machine for controlling the release of the locking frame, and an operating handle of the adding machine for actuating the locking frame when released.

12. In a combined typewriting and adding machine, the combination with the digit 110 keys of a typewriter, of devices actuated thereby, means for retaining said devices in their actuated positions, locking means for the keys, means for latching said locking 115 means in operative position, manipulative adding machine devices for returning the key actuated devices to normal position, and means controlled by the latter devices for unlatching the locking means. 120

13. In a combined typewriting and adding machine, the combination with the digit 125 keys of the typewriter, of devices actuated thereby, means for retaining said devices in their actuated positions, locking means for the keys, means for latching said locking means in operative position, manipulative adding machine devices for returning the key actuated devices to normal position, means controlled by the latter devices for 130

unlatching the locking means, and an operating handle of the adding machine for returning the locking means to inoperative position.

5 14. In a combined typewriting and adding machine, the combination with the digit keys of the typewriter, of means for locking the keys from operation, an adding mechanism, and means requiring an operation of 10 the adding mechanism to release the keys.

15. In a combined typewriting and adding machine, the combination with the digit keys of the typewriter, of means for locking the keys against operation, and manipulative devices for an adding machine for controlling the release of the keys.

20 16. In a combined typewriting and adding machine, the combination with the digit keys of the typewriter, of levers connected thereto, a space bar, a lock for said levers controlled by the space bar, manipulative devices for an adding machine for controlling the release of the lock, and an operating handle for an adding machine for releasing 25 the lock.

30 17. In a machine of the class described, the combination with a typewriting mechanism, of an independently operated adding mechanism, and means for preventing the operation of one of said mechanisms until the other has been operated.

35 18. In a machine of the class described, the combination with a typewriting mechanism having keys, of a calculating mechanism having keys manually operable independently of the keys of the typewriting mechanism, and interlocking means controlling the keys of one of the said mechanisms by the keys of the other of said mechanisms.

40 19. The combination with a typewriting machine, of a calculating machine, independently operated sets of manipulative devices for said machines, and means for controlling the manipulative devices of the calculating machine by the manipulative devices of the typewriting machine.

45 20. The combination with a typewriting machine, of a calculating machine, independent sets of manipulative devices for 50 said machines, and means for preventing the operation of the manipulative devices of

the calculating machine until the manipulative devices of the typewriting machine have been operated.

21. The combination with a typewriting machine, of a calculating machine, independent sets of keys for said machines, and means for preventing the operation of the keys of the calculating machine until the keys of the typewriting machine have been 60 operated.

22. The combination with manipulative devices of a typewriting machine, of manipulative devices of a calculating machine, the latter devices being normally locked, 65 means controlled by the manipulative devices of the typewriter for unlocking the manipulative devices of the calculating machine and then becoming locked, and means controlled by the manipulative devices of 70 the calculating machine for finally unlocking the typewriter manipulative devices.

23. In a machine of the class described, the combination with a typewriting mechanism including keys, of an adding mechanism having keys operable manually independently of the keys of the typewriting mechanism, means for controlling the keys of one of said mechanisms by the keys of the other of said mechanisms, and adjustable devices for disabling said controlling means at will.

24. In a machine of the class described, the combination with a typewriting machine including numeral keys, of a calculating machine having an operating handle and also including numeral keys, controlling devices adjusted in one sense by the typewriting keys, connections for adjusting said controlling devices in an opposite sense 80 by the calculating numeral keys, and devices actuated when said controlling devices are out of normal position, for preventing complete operation of said operating handle.

45 25. In testimony whereof I affix my signature in the presence of two witnesses.

WILLIAM H. MUZZY.
